STAPLING DEVICE

Henry Ruskin, Bayside, N.Y., assignor to Ace Fastener Corporation, Chicago, Ill., a corporation of Illinois Filed Feb. 8, 1960, Ser. No. 7,350

8 Claims. (Cl. 1—3)

This invention relates to a stapling device having a number of specific improvements which will be set forth in this specification. While these improvements are important singly they also, in combination, contribute to the production of a stapling device which is extremely compact, easily operable, and simple to manufacture.

The novel features of the stapling device of this invention are (1) the means for loading the device and automatically retracting the follower upon such loading, (2) the means employed for simple replacement of the follower retracting member, (3) the means used for aligning the rail within the magazine, (4) means used to assemble the top member to the cap of the stapling device, and (5) the means used to position the driver upon the cap of the stapling machine.

The means for loading may be briefly described as including, in a stapling machine having an open magazine, follower guide means therewithin, a follower operatively connected to said follower guide means, and a cover normally disposed upon the magazine and pivotally movable with respect thereto, the improvement which comprises spring means in operative relationship with the follower normally urging the follower forwardly, and flexible follower retracting means (preferably a doubled metal strip) operatively connected to the follower and the cover.

The means employed for simple replacement of the follower retracting member may be briefly described as comprising means for disengaging one end of the follower retracting means (preferably from the cover).

The means employed for aligning the rail within the magazine may be described as comprising a casing having its base split into right and left lateral portions, preferably longitudinal and of equal size. Each of the right and left portions of the casing are provided with a laterally disposed opening therewithin. A rail is secured within the casing and has a pair of oppositely disposed locating lugs each adapted to fit into one of the openings within the casing. Since only the base of the casing of the magazine is split into the aforesaid right and left portions the casing is laterally deformable prior to securement of the rail within the casing, and this fact permits the rail to be positioned accurately within the casing, the lugs, as will be described subsequently, permitting simple location of the rail within the casing.

In the preferred modification of this structure the upper portion of each of the lugs is offset from the base portion (preferably by 90 degrees). The offset portion of the lugs is designed to bear against guide means which are provided extending upwardly from the base.

The means employed to assemble the top member to the cap of the stapling machine comprise a cap member provided with a first opening and a second opening (the second opening being preferably paired). An upwardly movable member is disposed adjacent the first opening and a top member is provided overlying the cap member. The top member is formed with a first and a second downwardly depending member (the second downwardly depending member being preferably paired) which are disposable within the respective openings within the cap. The first downwardly depending member has a recess upon the leading side thereof which is adapted to accommodate the adjacent portion of the wall of the cap. The downwardly depending member disposable within the

2

second opening is initially slidably movable therein. The upwardly movable member is adapted to abut the trailing side of the first downwardly depending member when the adjacent portion of the cap is within the recess so as to hold the top member in place upon the cap.

The means used to position the driver upon the cap of the stapling machine comprise a cap construction having a pair of laterally spaced lugs upon the underside thereof with an offset driver blade disposed between the lugs.

In addition to the apparatus constructions claimed in this application, the application also includes claims to the novel method of securing the rail to the magazine of the machine so as to position the parts accurately and to the novel method of securing the top member of the cap of the stapling machine.

Aside from the objects of this invention set forth above other objects and advantages of the construction of this invention and the methods claimed will be apparent to the reader as this description proceeds.

The invention will be further described by reference to the accompanying drawings which are made a part of this specification.

FIG. 1 is a side perspective view of a stapling machine made in accordance with this invention.

FIG. 2 is a side view, partly in section, of the stapling machine shown in FIG. 1 showing the top member and cap construction of this invention.

FIG. 3 is a sectional view of the stapling machine shown in FIG. 2 taken along lines 3—3 of FIG. 2.

FIG. 4 is a side view of the stapling machine similar to that of FIG. 1 but with a portion about the guide members upon the base of the machine broken away to show the internal construction.

FIG. 5 is a detail sectional view of the stapling machine shown in FIG. 4 taken along lines 5—5 of FIG. 4.

FIG. 6 is a detail sectional view of the stapling machine shown in FIG. 4 taken along lines 6—6 of FIG. 4.

FIG. 7 is a side view of a stapling machine made in accordance with this invention with the cover thereof partially removed from its normal position above the magazine so as to show the details of construction, portions of the cover are broken away to show the internal construction.

FIG. 8 is a sectional view of the stapling machine shown in FIG. 7 taken along lines 8—8 of FIG. 7.

FIG. 9 is a sectional view of the stapling machine shown in FIG. 7 taken along lines 9—9 of FIG. 7.

FIG. 10 is a side perspective view of the rail used within the magazine casing of the stapling machine of this invention.

FIG. 11 is a side perspective view of the magazine casing of the stapling machine of this invention.

FIG. 12 is a side perspective view of the assembled magazine casing and rail of the stapling machine of this invention with portions of the magazine casing broken away to show the internal construction.

FIG. 13 is a fragmentary side view of a stapling machine made in accordance with this invention with the cover thereof in partially open position with respect to the magazine.

FIG. 14 is a sectional view of the stapling machine shown in FIG. 13 taken along lines 14—14 of FIG. 13.

FIG. 15 is a sectional view of the stapling machine shown in FIG. 14 taken along lines 15—15 of FIG. 14.

FIG. 16 is a fragmentary sectional view of the magazine and associated parts of the stapling machine shown in FIG. 14 taken along lines 16—16 of FIG. 14.

FIG. 17 is a sectional view of the stapling machine shown in FIG. 14 taken along lines 17—17 of FIG. 14.

FIG. 18 is a bottom plan view of the stapling machine

of this invention with the bottom cover portion of the machine removed to show the parts involved.

FIG. 19 is a bottom plan view of the magazine of the stapling machine of this invention.

Referring now to the specific form of the stapling machine shown in the drawings for a detailed description thereof, the machine 11 of this invention is formed with a base 12, an anvil 13 disposed upon base 12, a pair of guide members 14 extending upwardly from base 12, and an open magazine pivotally connected to base 12.

Anvil 13 bears a pair of spaced downwardly depending supports 16 which extend through openings within base 12. A spring 17 is disposed between supports 16. Anvil 13 is movable upon base 12 and a pair of mating detent portions 40b and 41b are provided on the base 12 and spring 17 so that anvil 13 assumes two specific positions upon base 12.

Anvil 13 bears pinning recess 18 and clinching recess 19 (FIG. 1) which may be selectively positioned beneath magazine 15.

An upstanding connecting member 20 is provided and is divided into bifurcated portions 25. Each of portions 25 is partially disposed within a recess 26 within base 12.

A securing member 27, a part of guide members 14 and joining said members to one another, is also provided which is secured to base 12 by rivets 28. Securing member 27 also bears recesses 29 alignable with recesses 26.

A lower support member 31 is disposed between bifurcated portions 25 of connecting member 20. Support member 31 is supported in recess 26 in base 12 by securing member 27.

An upper support portion is also provided between the bifurcated portions 25 of connecting member 20. Upper support portion 32 is an integral part of connecting member 20.

A spring 33 is disposed between lower support member 31 and upper support member 32. The entire spring and support members assembly is supported in place by securing member 27 beneath base 12.

Recesses 26 and 29 within base 12 are slightly larger than the portions of member 20 disposed therewithin so that member 20 is pivotally movable with respect to base 12.

The upper parts of each of members 25 are formed into hook portions 34 (FIG. 17). Hook portions 34 are disposable within recesses 35 (FIG. 14) located at the base 36 of magazine 15.

A front foot 37 and a rear foot 38 are secured to base 12 by securing members 39.

A bottom cover 22 is formed with a tongue 40a (FIG. 15) which is disposable within a recess 41a located within front foot 37. Bottom cover 22 is also formed with a pair of springable clips 24 which are secured to downwardly depending portion of securing member 27 when the cover is in place.

Magazine 15 is formed of casing 40 and rail 47. Casing 40 is formed with a base 41 which is divided into right and left portions 42 and 43. Portions 42 and 43 are joined to one another by front portion 44.

Casing 40 is also provided with lateral openings 45 within portion 42 and additional lateral openings 46 within portion 43. Rail 47 is disposed within casing 40. Rail 47 is formed with locating lugs 48 which are adapted to be at least partially disposed within openings 45 and 46. Each of lugs 48 is formed of a base portion 49 and an offset upper portion 50.

Rail 47 is secured to casing 40 by rivets 51a (FIGS. 14, 16 and 19) and also by portions 94 of casing 40 being driven into holes 95 in rail 47.

Base 41 of casing 40 is also provided with slots 35 therewithin. Rail 47 is also provided with slots 52 therewithin. Slots 35 and 52 are adapted to partially register with one another when rail 47 is properly positioned upon casing 40 but slots 35 and 52 are also partially out of registration as shown at 53 (FIGS. 14 and 19). Hook por-

tions 34 of connecting member 20 are adapted to be disposed within the registering portions of slots 35 and 52 with hook portions 34 abutting only the forward portions of the slots in normal latched position.

Rail 47 is also formed with a rear upstanding portion 54 which is provided with a hole 55 therethrough. Rail 47 also bears a front upstanding portion 56 which is also provided with a hole 57 therethrough. Rail 47 also has upstanding sides 58. A pair of depressions 65 partially extending through casing 40 at the interior thereof are likewise provided.

When rail 47 is properly aligned within casing 40 a space 59 is provided between the forward portion of casing 40 and the front of rail 47. Space 59 registers with space 66 within casing 40 (FIG. 19) so as to provide a staple ejecting channel.

A follower guide 60 is partially disposed within holes 55 and 57 and is held in position by snap ring 67. A follower 62 is also disposed upon rail 47 and upon follower guide 60. A follower spring is also disposed upon follower guide 60 behind follower 62.

A follower retractor 63 (FIGS. 7, 8, and 13) is formed of a doubled flexible element and is secured to follower 62 by rivet 64.

A cover 68 is pivotally disposed above magazine 15. Cover 68 is secured to magazine 15 by hinge pin 83 which passes through mating openings provided within cover 68, magazine 15, guides 14 and cap 79.

Cover 68 is also formed with depending sides 70 and 71. Side 70 of cover 68 is provided with spaced openings 72 and 73 and side 71 of cover 68 is provided with spaced openings 74 and 75. Clips 76 and 77 are also provided. The side portions of clips 76 and 77 are disposed within openings 72—74 and 73—75. The body portion 69 of clip 77 is disposed within the doubled portion of follower retractor 63 (FIG. 8). The side portions of clip 76 are adapted to abut slots 65 within casing 40 so as to removably secure cover 68 to magazine 15.

A tongue 78 is formed at the forward portion of cover 68.

A cap 79 is disposed above cover 68 and is provided with a first opening 80 and a spaced pair of second openings 81. An upwardly movable member 82 is part of cap 79 and is disposed adjacent first opening 80. Hinge pin 83 also passes through cover 68 and cap 79.

Cap 79 is also provided with lugs 84. Driver blade 85 is disposed between lugs 84 and is secured to cap 79 by holding extrusions 86. Driver blade 85 is also provided with a slot 87 through which tongue 78 passes.

Ram spring 88 is secured to cap 79 by rivets 89 and bears against the top of cover 68.

Top member 90 is disposed above cap 79 and is formed with a first downwardly depending member 91 and a pair of spaced second downwardly depending members. Member 91 is provided with a recess 93 upon the leading side thereof (FIG. 2). Member 91 is also disposable within opening 80 while members 92 are each disposable within an opening 81. Openings 81 are longer than each of members 92 while a wall of cap 79 can enter recess 93. This permits sliding movement of top member 90 along cap 79 to secure two parts to one another as will be subsequently explained.

The foregoing description sets forth the parts of the stapling machine of this invention. The operation thereof will now be explained.

The machine is loaded by moving cap 79 upwardly which causes the side portions of clip 76 to leave openings 65 within casing 40. This permits pivotal movement of cap 79, cover 68 and top member 90 (since the parts are secured to one another) and exposes rail 47 within magazine 15. Since follower retractor 63 is secured to cover 68 the movement of the parts causes retractor 63 to exert a rearward pull against follower 62 and moves this member rearwardly against the tension of follower spring 61.

The machine may now be loaded by placing staples (not shown) over rail 47. After this is done cap 79 is moved downwardly until the side portions of clip 76 snap into openings 65 within casing 40. This movement also releases the tension of retractor 63 from follower 62 permitting spring 61 to move follower 62 forwardly until stopped by the presence of staples in magazine 15. The machine can then be used to staple articles by pressing upon top member 90 which moves driver 85 downwardly and expels a staple into the work. The release of pressure upon top member 90 causes this member to assume its normal position because of the upward pressure exerted by spring 83.

When driver 85 is removed from the staple channel follower spring 61 moves follower 62 forwardly and positions another staple for operation.

It sometimes happens that follower retractor 63 breaks in operation of the machine and must be replaced. The construction of this machine is such that the replacement is a very simple matter. Follower retractor 63 is removed from its secured position to cover 68 by moving the slides of clip 77 towards one another. The sides can now be removed from openings 73-75 and retractor 63 disengaged from clip 77.

Snap ring 67 can then be removed from follower guide 60 and follower guide 60 moved longitudinally so as to remove it from openings 55 and 57. The assembly consisting of follower and follower retractor 63 can then be removed from follower guide 60 and a new assembly put in its place. Guide 60 can then be reinserted into openings 55 and 57, snap ring 67 placed into position and the replacement is completed.

The stapling machine of this invention can be easily converted into a tacker by merely pulling upon magazine 15. This exerts pressure upon hook portions 34 and causes connecting member 20 to move pivotally. This disengages hook portions 34 and permits base 12 to be moved out of alignment with magazine 15 to permit tacking. If the device is again to be used for stapling then realignment of base and magazine will cause hook portions 34 to again snap into position and lock the machine into stapling relationship.

The assembly of the stapling machine of this invention will now be described so as to illustrate other features of this invention.

Before proceeding with the description of the assembly the reader is advised that the specific order of assembly of parts set forth herein need not be strictly followed. Persons skilled in this art could make variations which would still fall within the scope of this invention.

The assembler of the device of this invention takes base 12 and positions connecting member 20, lower support member 31, upper support member portion 32 and spring 33 in proper relationship upon base 12. Guide members 14 having securing portion 27 thereupon is assembled to base 12 from the bottom and is riveted into place by rivets 28.

Anvil 13 is then brought into position upon base 12 with supports 16 thereupon disposed in the proper recesses provided in base 12. Spring 17 is then placed into position between supports 16.

Front foot 37 and rear foot 38 are then placed into position beneath base 12 and secured into place.

Cap member 79 is then taken by the assembler. Driver 85 is placed into position between lugs 84 within a bending fixture. The bending fixture also positions driver 85 into its proper position beneath cap 79. The fixture then bends lugs 84 about driver 85 and drives a portion of cap 79 into driver 85 forming holding extrusions 86 which firmly position driver 85 into place. Ram spring 83 is then placed into position beneath cap 79 and riveted into place by rivets 89.

Top member 90 is then placed into position upon cap 79. First downwardly depending member 91 is placed within first opening 80 within cap member 79 with the

recess within the leading side of member 91 adjacent the upper wall of member 90. Second downwardly depending members 92 of top member 90 are placed within the larger part of each of openings 81 within cap member 79. Top member 90 is then slid along cap 79 in the direction of the arrow shown in FIG. 2 until the abutting portion of the wall of cap 79 is disposed within recess 93 as shown in FIG. 2. Upwardly movable member 82 is then moved in the direction shown by the arrow in FIG. 2 adjacent movable member 82 into abutting relationship with member 91 to firmly position top member 90 upon cap 79.

In the preferred construction of the parts each of openings 81 are narrower in the direction of initial movement of top member 90 upon cap 79 so that the sides of the openings 81 cut into the members 92 and aid in proper positioning.

The cover 68 is then obtained by the assembler. Cover 68 is placed in side position and tongue 78 placed within slot 87. Cover 68 is then turned flat so as to lock the parts into operative relationship with one another.

Casing 40 of magazine 15 is then obtained by the assembler. Rail 47 is then obtained and right portion 42 and left portion 43 of casing 40 spread apart so that lugs 48 of rail 47 can be disposed within openings 45 and 46. After the parts are placed together then assembly of magazine and rail is placed into a locating fixture. The fixture spaces the front part of rail 47 from the front of casing 40 and positions the sides of casing 40 against intermediate portion 96 of rail 47 (FIG. 12).

When the parts are thus properly located the parts are doweled into place by driving portions of the casing 40 into holes 95 previously placed within rail 47. After this is done the rail 47 is permanently positioned within casing 40 by rivets 51a. This also prevents portions 42 and 43 from being spread apart again.

The above assembly also causes upper portions 50 of lugs 48 to extend beyond the outer walls of the magazine. Portions 50 are then utilized of journaling members abutting guides 14 and thus properly positioning magazine 15 with respect to anvil 13.

From the above description the reader will note that the rail 47 is positioned within casing 40 by using the inferior spacings only. Thus material thickness variations will not interfere with accuracy required.

After the magazine-rail assembly including casing 40 and rail 47 is put together the follower 62 is then obtained and assembled to follower retractor 63 by rivet 64 so as to produce an assembly consisting of follower and retractor. Snap ring 67 is then slipped upon follower guide 60 behind the recess (not shown) within guide 60 for the reception of ring 67. Follower guide 60 is then put through hole 57 in rail 47 and moved forwardly as far as it can go. Follower 62 is then disposed upon guide 60 and spring 61 disposed behind follower 62. The rear end portion of follower guide 60 is then placed within hole 55 and guide 60 moved rearwardly until the recess within guide 60 (not shown) is disposed just behind front tab 56 of rail 47. Ring 67 is then snapped into position to hold the parts in place.

Clip 76 is then assembled to cover 68 by moving the sides thereof inwardly and then releasing the sides into openings 72-74. The body portion 69 of clip 77 is placed within the doubled portion of retractor 63 and clip 77 then secured to cover 68 by moving the sides thereof inwardly and releasing them into openings 73-75 so that retractor 63 is in place.

The mating openings within guide members 14, magazine 15 and cap 79 are aligned and hinge pin 83 driven through the openings to secure the parts to one another.

The materials used in the construction of the parts of the stapling machine of the instant invention are the usual materials employed for such purposes or materials which could be utilized.

The preferred material for top member 90 is impact resistant plastic but the member could be made of metal,

wood, or similar material. The follower retractor 63 is preferably made of flexible metal shim stock but could also be made of tear resistant plastic such Mylar or it could be made of fabric, rubber, etc.

The remaining parts of the machine are preferably made of metal having the properties required by the parts.

The foregoing specific embodiments of this invention as set forth in the specification herein are for illustrative purposes and for purposes of example only. Various changes and modifications could obviously be made within the spirit and scope of this invention and would occur to those skilled in this art.

I claim:

1. A stapling machine comprising, in combination, a base, an anvil and guide means upon said base, an open magazine pivotally connected to said base, provided with lateral lug accommodating openings therein and spaced from said base, spring means operatively connected to said magazine and to said base, said magazine having a rail secured therewithin formed with a pair of oppositely disposed locating lugs adapted to lie adjacent the outer surfaces of opposite sides of said magazine and abut said guide means, follower guide means disposed within said magazine, a follower operatively connected to said follower guide means, a cover normally disposed upon said magazine and pivotally movable with respect thereto, spring means in operative relationship with said follower normally urging said follower forwardly, disengageable flexible follower retracting means operatively connected to said follower and said cover, complementary fastening members upon the sides of said magazine and said cover, a cap pivotally connected to said cover and overlying the same, spring means operatively connected to said cover and to said cap, a pair of laterally spaced lugs upon said cap, a bent driver blade disposed between said lugs, means connecting one end of said cover to said driver blade, said cap being also provided with a first opening and a second opening therewithin and a member adjacent said first opening; a top member formed with a first and a second downwardly depending member smaller than said openings disposable within the respective openings within said cap, the downwardly depending member disposable within said above-named first opening having a recess on the leading side thereof adapted to accommodate the adjacent portion of said cap, said adjacent member being adapted to abut the trailing side of said first downwardly depending member when the adjacent portion of said cap is within said recess so as to hold said top member in place.

2. A stapling machine comprising, in combination, a base, an anvil and upstanding guide means upon said base, an open magazine provided with a discharge opening pivotally connected to said base, spring means operatively connected to said magazine and to said base and normally holding said magazine in spaced relationship with said base, a rail secured within said magazine having two spaced pairs of oppositely disposed locating lugs adapted to lie adjacent the outer surfaces of opposite sides of said magazine and abut said guide means, said magazine being also provided with two spaced pairs of oppositely disposed lateral recesses permitting said lugs to pass therethrough, a follower guide rod secured within said magazine, a follower movable upon said follower guide rod, a cover normally disposed upon said magazine and pivotally movable with respect thereto, coil spring means upon said follower guide rod disposed behind said follower and normally urging said follower towards the discharge opening of said magazine, a removable flexible follower retractor secured to said follower and to said cover, complementary fastening members upon the sides of said magazine and the sides of said cover, a cap pivotally connected to said cover and overlying the same, leaf spring means connected to said cap and slidably bearing against said cover, normally holding said cover in spaced relationship to said cap, a pair of laterally

spaced lugs upon the underside of said cap, a bent staple driver having a driving portion and a holding portion disposed between said lugs, the driving portion being disposable within the discharge opening of said magazine, means holding the holding portion to said cap, means slidably connecting one end of said cover to the driving portion of said driver blade, said cap being also provided with a first opening and a pair of spaced second openings therewithin, and a member adjacent said first opening; a top member formed with a first downwardly depending member and a pair of spaced second downwardly depending members disposable within the respective openings within said cap, and smaller than said openings, the downwardly depending member disposable within said above-named first opening having a recess on the leading side adapted to accommodate the adjacent portion of said cap, said adjacent member being adapted to abut the trailing side of said first downwardly depending member when the adjacent portion of said cap is within said recess so as to hold said top member in place.

3. A stapling machine comprising, in combination, a base, an anvil and a spaced pair of upstanding guide means upon said base, an open magazine in spaced relationship with said base provided with a discharge opening therewithin, spring means operatively connected to said magazine and to said base, a rail secured within said magazine having two spaced pairs of oppositely disposed locating lugs adapted to lie adjacent the outer surfaces of opposite sides of said magazine and abut said guide means, said magazine being also provided with two spaced pairs of oppositely disposed lateral recesses permitting said lugs to pass therethrough; a follower guide rod secured within said magazine, a follower longitudinally movable upon said follower guide rod, a cover normally disposed upon said magazine and pivotally movable with respect thereto, a tongue portion on one end of said cover, a coil spring upon said follower guide rod disposed behind said follower and normally urging said follower toward the discharge opening of said magazine, a flexible follower retractor formed of a doubled member, the free edges of said follower retractor being permanently secured to said follower, a removable clip secured to said cover and to said folded edge portion of said follower retractor, complementary fastening members upon the sides of said magazine and the sides of said cover; a cap pivotally connected to said cover and overlying the same, leaf spring means connected to the underside of said cap, downwardly depending therefrom, and slidably bearing against said cover, said leaf spring means normally holding said cover in spaced relationship to said cap, a pair of laterally spaced lugs upon the underside of said cap, a bent staple driver having a driving portion and a holding portion disposed between said lugs, the driving portion of said staple driver being disposable within the discharge opening of said magazine, means holding the holding portion of said staple driver to said cap, said staple driver being also provided with a slot in the driving portion thereof, said slot slidably accommodating the tongue of said cover so as to connect one end of said cover to the driving portion of said driver blade, said cap being also provided with a first opening and a pair of spaced second openings therewithin, and a member adjacent said first opening; a top member formed with a first downwardly depending member and a pair of spaced second downwardly depending members disposable within the respective openings within said cap and smaller than said openings, the downwardly depending member disposable within the above-named first opening having a recess on the leading side adapted to accommodate the adjacent portion of said cap, the downwardly depending members disposable within said above-named second openings being initially slidably movable therewithin, said adjacent member being adapted to abut the trailing side of said first downwardly depending member

when the adjacent portion of said cap is within said recess so as to hold said top member in place.

4. A stapling machine element comprising a cap member provided with a first opening and a second opening, a lock member secured to said cap and adjacent said first opening; a top member overlying said cap member formed with a first and a second downwardly depending member disposed within the respective openings within said cap, the downwardly depending member disposed within said second opening being shorter than the length of said opening, the downwardly depending member disposed within said above-named first opening having a recess on the leading side thereof accommodating the adjacent portion of said cap, said lock member being upwardly movable and abutting the trailing side of said first downwardly depending member so as to hold said top member in place upon said cap.

5. A stapling machine as set forth in claim 4 wherein a pair of spaced second openings and a pair of second downwardly depending members are provided.

6. A magazine for a stapling machine comprising a casing having its base split into right and left portions, each of said right and left portions being provided with a laterally disposed opening therewithin, a rail secured within said casing having a pair of oppositely disposed locating lugs each adapted to fit into one of said openings within said casing, said casing being laterally deformable prior to securement of said rail therewithin so as to permit insertion of said rail within said magazine, the lugs upon said rail further permitting simple location of said rail with respect to said casing.

7. A magazine for a stapling machine comprising a casing having its base longitudinally split into equal right and left halves, each of said right and left halves being

5 provided with a pair of spaced laterally disposed opening therewithin, a rail secured within said casing having two pairs of oppositely disposed locating lugs wherein each lug is adapted to fit into one of said openings within said casing, said casing being laterally deformable prior to securement of said rail therewithin so as to permit insertion of said rail within said magazine, the lugs upon said rail further permitting simple location of said rail with respect to said casing.

10 8. In a stapling machine having a base, an anvil and guide means upon said base, the improvement which comprises a magazine comprising a casing having its base split into right and left portions, each of said right and left portions being provided with a laterally disposed opening therewithin, a rail secured within said casing having a pair of oppositely disposed locating lugs each adapted to fit into one of said openings within said casing, each of said lugs having a base portion and an offset upper portion, said casing being laterally deformable 15 prior to securement of said rail therewithin so as to permit insertion of said rail within said magazine, the lugs upon said rail further permitting simple location of said rail with respect to said magazine, the offset upper portions of said lugs being adapted to bear against said guide 20 means.
